UNITED STATES PATENT OFFICE.

JAMES E. BANCROFT, OF TOLEDO, OHIO, ASSIGNOR TO THE NATIONAL CEMENT AND RUBBER MANUFACTURING COMPANY, OF SAME PLACE.

HYDROCARBON-BURNER.

SPECIFICATION forming part of Letters Patent No. 626,405, dated June 6, 1899.

Application filed December 17, 1897. Serial No. 662,245. (No model.)

To all whom it may concern:

Be it known that I, JAMES E. BANCROFT, of Toledo, county of Lucas, and State of Ohio, have invented certain new and useful Improvements in Hydrocarbon-Burners; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention relates to a hydrocarbon-burner, and has for its object to provide a vaporizer formed in the shell of the burner and surrounding a combustion-chamber, with which said vaporizer is connected by a pipe having a valve-controlled jet-orifice adapted to discharge into said combustion-chamber, the combustion-chamber being rotatable in a vertical plane.

In the drawings, Figure 1 is a side elevation of a burner constructed in accordance with my invention. Fig. 2 is a rear elevation in which the starting-pan is omitted; and Fig. 3 is a vertical cross-section on line xx , Fig. 1.

1 designates a burner, comprising conical portions 2 and 3, having their smaller ends 4 and 5 located in inverse relation to each other, and at the base 6 of the conical portions, centrally of the burner, there is formed within the shell thereof a plurality of communicating vaporizing-chambers 7, located around the periphery of the heating-chamber, as shown in Fig. 3. At the point of the heating-chamber there is also formed a projecting coupling 9, threaded internally for securing the burner to the hydrocarbon-conduit 10, having secured thereto a swivel-coupling 11, which allows the burner to be placed in a horizontal position, and is secured to a stationary conduit 12, communicating with the hydrocarbon-reservoir. (Not shown in the drawings.) The vaporizing-chambers 7 are closed by means of plugs 13, engaging coincident screw-threaded portions formed at the outer ends 14 of the chambers.

14 designates a vapor-duct located at the periphery of the conical portions 2, being in-

tegral therewith and communicating with the vaporizing-chambers 7 at the point 15, thereby causing the hydrocarbon entering through the conduit 10 into the vaporizing-chamber 7 to travel circumferentially to the burner. 55 The vaporized hydrocarbon is led through the conduit 14 to a needle-valve 16 through a pipe 17, which is secured to the conduit 14 at the point 18. The conical portion 2 is perforated, as shown in Figs. 1 and 2, for the admittance of air, which is induced to enter into the burner by the force of the vapor escaping the needle-valve 16. The escaping vapor and the air drawn into the perforated conical end portions are intimately intermingled at 65 the enlarged central portion 19, and the lighted gases are projected through the tapering end portion 5.

In the initial operation the burner is set in a vertical position and is adapted to assume 70 this position by means of the swivel connection 11, and the needle-valve is then opened, allowing a portion of the fluid hydrocarbon to escape into a pan-shaped disk 20, having a conduit formed therein. The liquid hydrocarbon in the pan is lighted and the heat therefrom vaporizes the hydrocarbon contained in the heating-chamber and the ducts leading to the needle-valve 16. Proportionally to the consumption of the hydrocarbon 75 in the pan the valve 16 is again opened, allowing the generated vapors to escape through the said valve and burn in the interior of the burner. When the liquid hydrocarbon is all consumed, the valve is opened, allowing the 80 hydrocarbon to escape, and the burner is caused to assume its horizontal or inclined position simultaneously with the opening of the valve 16. The vapor escaping through the valve, which is centrally located in the 85 aperture of the end of the conical portion 2, causes an inward flow of air through the perforations and the central aperture of the conical portion 2. The vapor intimately intermingles with air in the centrally-enlarged portion of the burner and the flame is projected through the conical end portion 5. The intensity of the flame is adjusted by means of the needle-valve 16, which allows more or less of the vapor to escape.

It has been found that after the vaporizing-burner has been used for a period of time the interior thereof is coated with a deposit, decreasing the passage for the vapor and hydrocarbon through the same, necessitating the removal of the coating, and for which purpose I have provided each separate chamber with a removable plug, thereby allowing access to each chamber for removing such deposits or coatings from the interior walls of the chambers.

I have also found that with a burner constructed in accordance with my invention the escaping vaporized hydrocarbon and air are more intimately intermingled in the combustion-chamber, generating a more intense heat than has heretofore been accomplished.

It will be seen that in the foregoing description I have described a burner used for brazing-furnaces, but, however, without departing from the spirit of my invention may em-

ploy the same burner for torches or other analogous purposes having for their object to vaporize the hydrocarbon previous to combustion.

25

What I claim is—

A hydrocarbon-burner comprising a combustion-chamber, a vaporizer surrounding said chamber, a pipe connected with the vaporizer and having a valve-controlled jet-orifice adapted to discharge into said combustion-chamber, a starting-pan surrounding said jet-orifice, and means for rotating the burner in a vertical plane.

30

In testimony that I claim the foregoing as my own I hereby affix my signature in presence of two witnesses.
